(57) **CLAIM**

The ornamental design for an eyeglass, as shown and described.

DESCRIPTION

FIG. 1 is a front perspective view of an eyeglass of the present invention;

FIG. 2 is a front elevational view of the eyeglass of FIG. 1; FIG. 3 is a rear elevational view of the eyeglass of FIG. 1; FIG. 4 is a left side elevational view of the eyeglass of FIG. 1, the right side elevational view being a minor image thereof; FIG. 5 is a top plan view of the eyeglass of FIG. 1; and, FIG. 6 is a bottom plan view of the eyeglass of FIG. 1. The broken lines shown in FIGS. 1-6 are for illustrative purposes only and form no part of the claimed design.

1 Claim, 4 Drawing Sheets
